ROTARY PUMP OR COMPRESSOR

Charles E. Yates, Lakewood, Ohio

Application May 27, 1935, Serial No. 23,579

6 Claims. (Cl. 230—177)

This invention relates to rotary pumps or compressors and more particularly to that type of pumping equipment which consists of an enclosed cylindrical chamber in which is a hollow rotative sleeve. This sleeve has two or more symmetrically positioned transverse bores each of which contains a piston which may be reciprocated therein by means of an eccentrically positioned shaft which passes longitudinally through the assembled parts and is journaled in the ends of the enclosing chamber. The aforementioned parts are so located and proportioned that rotation of the shaft causes oscillation of the pistons in their respective chambers and rotation of the sleeve at a speed which is one-half that of the eccentric shaft. Ports provide ingress and egress for the pumped medium.

Known machines of this type have been so constructed as to take in and discharge the pumped fluid through oppositely positioned ports in the outer casing. This has limited the ratio between the piston diameter and the sleeve diameter to such dimensions as will insure that the piston chamber is not at any time open to both the intake and discharge ports. The general dimensions have also been limited to provide that the pistons shall each provide a continuous cut-off between the adjacent parts of the sleeve interior. The construction disclosed herein includes but one casing wall port, hence the limitation of ratios is not required. Also this construction does not require that the pistons maintain continuous interior walls, therefore there are no ratio limitations for that reason.

Machines of this class have hitherto required packing glands of heavy and complicated construction due to the pressure which builds up in the interior of the sleeve assembly. The construction disclosed herein makes this portion a part of the suction line to the compressing members thereby maintaining low pressures therein and making power-consuming, expensive packing glands unnecessary.

Machines of this class have hitherto been uncertain in starting as lubricant may accumulate in the pump interior and pass into the compression chambers during idle periods. This accumulated liquid prevents the oscillation of the pistons in their bores and consequently prevents the movement of the pump parts. The improved construction disclosed herein removes any liquid as it accumulates and thereby insures a start every time power is applied.

Machines of this class have hitherto not worked at all times to their maximum efficiency if the

discharge head has been a variable, and it has been necessary to open the discharge port at an average point and suffer losses at either lower or higher pressures. The improved construction herein disclosed permits the operation at any head with maximum efficiency.

Generally speaking the object of this invention is to provide new and useful improvements in the art of this class of rotary pump that will remove dimensional limitations, make the use of complicated packing glands unnecessary, make sure that the pump will be able to function whenever power is applied and insure maximum efficiency against any head pressure.

Referring to the drawings:

Figure 1 is a longitudinal cross-section of the compressor except the shaft which is shown in elevation;

Figure 2 is an end-view cross-section through 2—2 of Figure 1;

Figure 3 is an enlarged partial cross-section through 3—3 of Figure 1 showing the inclusion of restrictive valves in the discharge ports; and

Figure 4 shows the compressor in assembly with an oil separator-container.

The pump consists of an enclosed cylindrical chamber 11 as shown in Figure 1, with a sleeve 12 therein which is a running fit. This sleeve may be supported entirely by the chamber or be so journaled as to have its weight carried free of the chamber without interference with its rotation therein. This sleeve has two transverse bores 13 and 13' at right angles to each other. In each of these bores is a piston 14 and 14' which is a running fit in the bore. The length of the piston 35 with relation to the thickness of the sleeve wall is such that when one end of the piston is at the outward end of its travel the other end is partially withdrawn from the inner end of the bore in the sleeve. Their dimensions and design are such that a sufficiently continuous bearing in the sleeve is provided throughout the entire oscillatory travel of the piston without offering a barring wall around or by the piston at any time. The driving shaft 15 passes longitudinally through the sleeve and symmetrically placed eccentrics 16 and 16' thereon locate in the bores provided in the pistons. The journals for the shaft in the ends of the chamber are eccentric to the bore of the enclosing chamber to the amount of one-quarter of the full stroke of the pistons; the centers of the shaft eccentrics are also the same distance from the center of the driving shaft. A suitable port opening 17 and 17' opposite each piston is provided in the wall of the enclosing 55

chamber, so located as to be radially in line with the end of the piston.

If the discharge head is to vary restrictive valves 18 may be placed in these ports as shown 5 in Figure 3.

When using this type of compressor against pressures which are such that it is necessary that the piston open the discharge port 17 before the pressure in the piston bore 13 has equalled that 10 in 17, the more highly compressed fluid is restrained from entering the bore 13 by valve 18. This valve will lift when the pressure in bore 13 exceeds that in port 17. Similarly, it will close as 15 soon as the piston 14 has reached its maximum outward radial travel thereby preventing any return of compressed fluid to the interior of the pump.

Where required a suitable means 19 for sealing against oil or fluid passage is provided at the 20 end of the chamber through which the driving shaft extends for connection to a propelling unit. This seal is not required if the pump is taking air at atmospheric pressure, if the suction pressure is the same as that surrounding the pump exterior or if the driving unit is tightly sealed into a common chamber with the pump assembly.

Lubrication is arranged in a manner which provides the ample supply of oil required for pumps of this class and in such a way that it may not 30 accumulate detrimentally as follows. An oil container 20 is provided either as a part of the chamber structure or separate therefrom and a conduit 21 is provided from the bottom of this container to the open end 22 of the hollowed drive shaft. 35 Obviously any increase in pressure at the entry to the drive shaft 22 or within the oil chamber 20 will cause a flow of oil from the container to the hollow shaft. This pressure may be induced either by means of an auxiliary oil pump or, more 40 simply, by subjecting the interior of the oil container to the discharge pressure of the pump. Such a means is shown in Figure 4 for purposes of illustration though no claims are made in this connection except in combination with the 45 other parts of this application. As shown the oil container 20 serves the dual purpose of reservoir and oil separator, as the excess oil coming through with the pump discharge line 23 is deposited in the container 20. Under certain circumstances 50 it may be necessary to lead the compressed fluid through a labyrinthian channel before permitting it to leave the container at 24, this to insure the complete elimination of oil from the discharge. The oil which has been introduced into the hollow shaft under pressure is released under the 55 bearings in the interior of the pump through suitable ducts 25 and is distributed to all points of the interior by means of capillary and centrifugal action. In certain applications it may be desirable 60 to reduce the oil pressure on the journals and other moving parts to a portion of that prevailing in the lubricant chamber. A suitable means for accomplishing this is the subject of another application.

65 In Figure 4, 28 is a one-way restrictive valve to allow the easy travel of fluid into the interior of the sleeve 26 through conduit 29 but to restrain any outward tendency through the conduit.

In operation the drive shaft 15, pistons 14 and 70 14' and sleeve 12 co-act and inter-act to produce a smooth even motion. The pistons are oscillated by the shaft eccentric and in turn they rotate the sleeve. This brings the compression chambers opposite their respective discharge 75 ports at the proper time and carries them away

from the ports at the point of maximum outward piston travel.

The intake to the compression chambers is through the hollowed axial interior 26 of the sleeve and over the top of each end of each piston 5 at the inward end of its travel, and by the sides of the piston through openings 27. It is obvious that there can be no pressure in the interior of the sleeve in excess of the suction pressure, consequently the need for complicated gland structures is eliminated.—they are not wholly unnecessary but undesirable.

It is equally obvious that with this improved method of construction that it is unnecessary to provide a continuous closure of the axial opening 15 at any point, it actually is now undesirable. An unrestricted opening will allow free passage of incoming fluid to the intake openings above the pistons.

It is equally apparent that lubricant or other 20 liquids which might impede action cannot accumulate in the sleeve interior as such liquids are centrifugally carried to the inner periphery of the sleeve and scavenged outwardly over the piston tops twice per revolution of the rotor 25 assembly.

What is claimed is:

1. The combination of a cylindrical casing having end walls and a channel through one of said walls, a rotor within said casing having a cylindrical bore extending longitudinally therethrough and forming within said rotor an inlet passage in communication with said channel, said rotor having a plurality of chambers diametrically disposed therethrough, pistons in said chambers and extending across said bore, said pistons being so proportioned to said rotor that there is free opening from one end of said rotor to the other through said bore, said pistons being adapted to open communication from said bore to said chambers at the extremities of their strokes, means to reciprocate said pistons and rotate said rotor including a longitudinal shaft extending through said bore and eccentrically disposed therein, said shaft having eccentricities thereon journalled directly in said pistons, said shaft having a lubricant passage therein, means in said channel to restrict the movement of fluid to the incoming direction, said casing having discharge ports, means cooperative with said discharge ports to restrict the movement of fluid therethrough to an outward direction, a lubricant chamber, a pressure passage from said outlet ports to said chamber, and a second lubricant passage from said lubricant chamber through one of said end walls to said first lubricant passage in said shaft, said shaft having lubricant holes from said first lubricant passage to the bearing surfaces of said shaft.

2. The combination of a cylindrical casing having exhaust ports, a rotor within said casing having a central bore extending longitudinally therethrough and forming an inlet passage therein for gaseous fluid, said rotor having a plurality of compression chambers extending diametrically therethrough and in angular relation to each other, pistons in said chambers and adapted at the inner ends of their strokes to provide openings between said chambers and said passage, 70 and means to reciprocate said pistons in said chambers and thereby rotate said rotor while exhausting fluid from said inlet passage through said openings, said driving means including a drive shaft eccentrically disposed through said 75

bore and having thereon eccentrics rotatably fitted in bores in said pistons.

3. The combination of a cylindrical casing having exhaust ports, a rotor within said casing having a central bore extending longitudinally therethrough and forming an inlet passage therein, said rotor having a plurality of chambers diametrically therethrough and in angular relation to each other, pistons in said chambers and extending across said bore, said pistons being proportioned to permit openings between the wall of said bore and said pistons at certain positions of the travel of said pistons, and means to reciprocate said pistons in said chambers and thereby 10 rotate said rotor while drawing fluid from said bore through said openings, said driving means including a drive shaft eccentrically disposed through said bore and having thereon eccentrics rotatably fitted in bores in said pistons.

20 4. The combination of a cylindrical casing having end walls and an inlet channel through one of said walls, a rotor within said casing having a cylindrical bore extending longitudinally therethrough in communication with said inlet channel, said rotor having a plurality of chambers diametrically through said rotor, pistons in said chambers and normally extending across said bore, said pistons being so proportioned to said bore that there is free opening around said pistons from one end of the rotor to the other longitudinally, said pistons being adapted to open communication from said free opening to said chambers at the bottom of their stroke, whereby a fluid to be compressed may be conducted to 30 said chambers, and means to reciprocate said pistons including a longitudinal drive shaft eccentrically disposed through said bore and carrying eccentrics rotatably fitted in bores in said pistons, said casing having discharge means adapted to 40 conduct compressed fluid from said chambers.

5. The combination of a cylindrical casing having end walls and a channel through one of said walls, a rotor within said casing having a cylin-

drical bore extending longitudinally therethrough and forming therein an inlet passage in communication with said channel, said rotor having a plurality of chambers diametrically through said rotor, pistons in said chambers and extending across said bore, said pistons being so proportioned to said rotor that there is free opening from one end of the rotor to the other longitudinally, means to reciprocate said pistons, said means including a longitudinal drive shaft eccentrically disposed through said bore and carrying eccentrics journalled directly in said pistons, said pistons being adapted to open fluid communication between said bore and said chambers at the extremities of their strokes, said casing having discharge ports, and means cooperative with said ports to restrict the movement of fluid therethrough to an outward direction.

6. The combination of a cylindrical casing having end walls and a channel through one of said walls, a rotor within said casing having a cylindrical bore extending longitudinally therethrough and forming therein an inlet passage in communication with said channel, said rotor having a plurality of chambers diametrically through said rotor, pistons in said chambers and extending across said bore, said pistons being so proportioned to said rotor that there is free opening from one end of the rotor to the other longitudinally, said pistons being adapted to open communication between said bore and said chambers at the extremities of their strokes, means in said channel in the casing to restrict the movement of fluid to the incoming direction, said casing having discharge ports, means associated with said discharge ports to restrict the movement of fluid to an outward direction, a drive shaft journalled in said end walls and eccentrically disposed through said bore, and eccentrics on said drive shaft, said eccentrics being journalled directly in said pistons.
